UNITED STATES PATENT OFFICE.

ARTHUR J. MORRILL AND LUKE W. NORTHFIELD, OF MINNEAPOLIS, MINNESOTA; SAID MORRILL ASSIGNOR TO SAID NORTHFIELD.

MILK-PAIL SUPPORTER.

SPECIFICATION forming part of Letters Patent No. 700,220, dated May 20, 1902.

Application filed December 16, 1901. Serial No. 86,125. (No model.)

To all whom it may concern:

Be it known that we, ARTHUR J. MORRILL and LUKE W. NORTHFIELD, citizens of the United States, residing at Minneapolis, in the county of Hennepin and State of Minnesota, have jointly invented certain new and useful Improvements in Milk-Pail Supporters, of which the following is a specification.

Our invention relates to pails for use in milking; and the object of the improvement is the provision of simple and efficient means for enabling the pail to be conveniently supported between the knees of the person doing the milking, the supporting devices being permanently though loosely connected to the pail and in readiness to be adjusted for use in supporting the pail, but adapted to gravitate to its sides and out of the way when not in use.

Stated in a general way, the improvements consist in combining with the pail and ears of suitable form suitable pail-supporters adapted to swing from and coöperate with the ears and pail-top and normally depend at the sides of the pail and to be lifted to positions approximately horizontal and at right angles thereto for supporting the pail on the knees while in use.

Our improvements are illustrated in the accompanying drawings, in which—

Figure 1 is a central vertical section of a pail provided with the improvements. Fig. 2 shows a front elevation, partly sectional, of a portion of the pail, one of its ears, and one of the supporting devices. Fig. 3 shows the same parts as Fig. 2, viewed from a position nearly at a right angle to and from the left of Fig. 2; and Fig. 4 is a plan view of the same parts.

In the drawings, 1 designates a pail, 2 its bail, and 3 the ears to which the bail is connected through openings in the usual way. Each ear 3 has its opposite edges cut away at about the level of the top bead 4 of the pail to form sockets 5 for receiving the pail-

supporters. These supporters or pail-holders 6 are preferably made of wire and comprise a main or outer portion 7, formed of parallel branches looped or connected at their outer ends, as at 8, and an inner portion 9, 50 that is bent downward at nearly a right angle to the main portion 7. In normal position the supporter hangs at the side of the pail, as indicated in Fig. 1, its bent portion 9 engaging the middle portion of the ear 3 55 and the top of the pail. When raised to approximately horizontal position, the bent portion 9 bears against the inner edge of the bead 4 or top of the pail, the under surfaces of the stems of the main portion 7 resting on 60 the top of the bead or rim of the pail and their upper surfaces bearing against the top walls or shoulders of the sockets 5 in the ears, and are thereby locked against further upward movement. In this position the supporters serve efficiently to sustain the pail between the knees or other objects they may be made to rest upon. When the pail is lifted, the supporters gravitate to their normal positions at the sides of the pail, as indicated in Fig. 1.

Having described our invention, what we claim, and desire to secure by Letters Patent, is—

The combination with a pail and its ears, 75 the ears having their edges suitably recessed; of pail-supporters, comprising body portions extending outward from the ears and downwardly-bent portions extending inward from the ears, arranged to engage the ears in said 80 recesses and to bear upon the top portion of the pail, substantially as set forth.

In testimony whereof we have hereunto set our hands this 6th day of December, 1901.

ARTHUR J. MORRILL.
LUKE W. NORTHFIELD.

In presence of—
FRANK H. CASTNER,
HENRY BEDDOW.
